Des. 221,447
Patented Aug. 17, 1971

221,447

TILTABLE EXERCISE BOARD OR THE LIKE

John M. Brubaker, Star Rte., Box 48,
Hammett, Idaho 83627

Filed Mar. 30, 1970, Ser. No. 22,085

Term of patent 14 years

Int. Cl. D21—03

U.S. Cl. D34—5

FIG. 1 is a right front perspective view of the tiltable exercise board or the like embodying my new design.

FIG. 2 is a left rear perspective view as viewed from the bottom.

I claim:

The ornamental design for a tiltable exercise board or the like, substantially as shown.
